(80) **Hague Agreement Data**

(57) **CLAIM**

Int. Filing Date: **Jan. 3, 2025**

The ornamental design for an electric bicycle as shown and described.

Int. Reg. No.: **DM/243708**

DESCRIPTION

Int. Reg. Date: **Jan. 3, 2025**

Int. Reg. Pub. Date: **Feb. 7, 2025**

1. Electric Bicycle

(30) **Foreign Application Priority Data**

1.1 : Perspective

Jul. 12, 2024 (CN) 202430435473.9

1.2 : Perspective
